CLAIM

The ornamental design for a adjustable height pet bowl, as shown and described.

DESCRIPTION

FIG. 1 is a front, right and top perspective view of a adjustable height pet bowl showing my new design; FIG. 2 is a front, right, and top perspective view thereof, but shown with the pet bowl raised in a first position of use for clarity of illustration.

FIG. 3 is a front, right, and top perspective view thereof, but shown with the pet bowl raised in a second position of use for clarity of illustration.

FIG. 4 is a front view of FIG. 1;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged detail view of area 10 shown in FIG. 4.

The dash-dash broken lines illustrate portions of the adjustable height pet bowl. FIGS. 4 and 10 show dash-dot broken lines that represent the boundaries and indicators of the enlarged views. The broken lines form no part of the claimed design.
